[57] CLAIM

The ornamental design for a cosmetic box, substantially as shown and described.

DESCRIPTION

FIG. 1 is a perspective view of a cosmetic box or the like showing my new design in open position.

FIG. 2 is a top plan view of the cosmetic box.

FIG. 3 is a front elevational view of the cosmetic box.

FIG. 4 is a rear elevational view of the cosmetic box.
FIG. 5 is a side elevational view of the cosmetic box,
the opposite side being a mirror image thereof.
